ATTORNEY

UNITED STATES PATENT OFFICE.

CHARLES N. MORGAN, OF ALBANY, AND ANDREW L. KEELER, OF TROY, NEW YORK.

FURNACE-ARCH CONSTRUCTION.

Application filed March 22, 1924. Serial No. 701,085.

To all whom it may concern:

Be it known that we, CHARLES N. MORGAN and ANDREW L. KEELER, citizens of the United States, and residing, respectively, at 5 Albany, in the county of Albany, State of New York, and Troy, in the county of Rensselaer, State of New York, have invented new and useful Improvements in Furnace-Arch Constructions, of which the 10 following is a specification.

Our invention relates to furnace arches, and particularly to the end construction of furnace arches of any type.

In arches of this character, due to the 15 intense heat to which they are exposed, it is necessary to provide for considerable expansive movement of the structure, and also to protect the steel work which supports the refractory portion of the arch from the direct influence of the furnace gases. The 20 inner end of the arch, adjacent the boiler, which is exposed to particularly intense heat, is so designed as to form a base or support for the superimposed curtain wall 25 which extends upwardly from the arch to the boiler, and it is desirable that the refractory units in this part of the arch should be so designed and supported as to be readily removable and renewable without 30 substantially disturbing the curtain wall above, or other portions of the arch structure.

The objects of our invention, therefore, 35 are to provide an end construction for a furnace arch which will permit the necessary expansive movement of the structure without destroying or injuring its integrity; which will thoroughly protect the steel work from the influence of the hot 40 furnace gases; which will be supported entirely independently of the main arch; and in which disintegrated blocks may be readily removed and renewed without substantially disturbing portions superimposed 45 thereon and normally supported thereby.

We accomplish these objects by utilizing 50 the novel form of refractory blocks and means for supporting these blocks, together with the novel arrangement and combination of these with other features illustrated in the accompanying drawing, in which—

Fig. 1 is a fragmentary perspective view

of our end construction shown in connection with a suspended flat arch;

Fig. 2 is a fragmentary elevation of our 55 end construction as viewed from inside the furnace;

Fig. 3 is a section of Fig. 2 on the line 3—3, showing details of the supporting means.

In the drawing, 1 represents the end blocks of the arch which may be substantially quadrantal in section, as shown. 2 represents in a general way the main arch, and 3, the curtain wall which has one course 60 of blocks supported on the corner blocks, 1. The corner or end blocks, 1, have an upper horizontal face, 5, a rear vertical face, 6, and are preferably but not necessarily provided with a curved face, 4, exposed to 65 the fire. The upper face, 5, of the end block is provided with a vertical channel, or recess, 7, extending across the block; and the rear face, 6, is provided with a similar channel or recess, 8, which extends horizontally across the rear of the block. These channels are respectively adapted to receive a vertical lug or lip 9, and a horizontal lug or lip, 10, of an angular metal hanger, 11, which extends around the upper 70 rear corner of the block. The weight of the block is supported upon lip, 10, and lip, 9, merely prevents the block from tipping forward. It will be noted that there is some space between the angular part of the 75 hanger, 11, and the block, 1, and between the outer sides of the lips and the channels, so that the block and hanger are somewhat loosely associated. This provides for expansion in the block itself. The hanger, 11, 80 is provided with an upwardly extending leg, 12, having a hooked end, 13, adapted to engage the flange of a standard channel, 14, which is attached to the bottom flange of the supporting I beam, 15. The bill of 85 the hook is short and fits rather loosely over the channel so as to permit the hanger and its associated block to swing or pivot freely to the front and upwardly about the edge of the channel, 14, as an axis. To hold 90 the hanger and its associated block in its proper position, and so that the faces, 5 and 6, are horizontal and vertical, respectively, the horizontal leg of the hanger ex-

60

tends substantially parallel to the web of the channel, 14, and is provided with a small, upwardly projecting boss or lug, 16, which rests against the web of the channel. 5 Supported upon the horizontal faces, 5, of the blocks, 1, is a course of blocks, 17. The blocks, 17, are of such length that they span two or more of the blocks, 1, and are of such height that they extend somewhat 10 above the upper flange of the I beam, 15.

The lintel blocks, 18, which support the superimposed curtain wall, break joints with the blocks, 17, and are carried by the I beam, 15. That portion of the lower face 15 of each block, 18, which extends over the course of blocks, 17, is notched out to provide a recess, 20, between the blocks, 17 and 18, which is sealed with some elastic, non-conducting and non-combustible substance, 20 such as asbestos, to form an expansion joint, 21. In practice, we prefer to make this joint from $\frac{1}{2}$ to $\frac{3}{4}$ inches in thickness.

From a consideration of the foregoing in connection with the drawing, it will be apparent that the expansive thrust of the main arch will swing the block, 1, and the hanger in an outward and upward direction about the edge of the channel, 14, as an axis, and that the movement will be absorbed in the 30 compression of the elastic material in the expansion joint, 21. It will also be apparent that any block, 1, may be conveniently removed by first removing only the block, 17, which is immediately above it. This 35 will permit the block, 1, and its associated hanger to be lifted from the channel so that a new block may be positioned on the hanger and placed in the arch. This operation will not disturb the curtain wall above for it 40 will be supported on the lintels, 18; and it is obvious that the main arch which is wholly separate from, and independent of our end construction will not be disturbed. Furthermore, since the end blocks, 1, cannot 45 swing inwardly beyond the vertical because of the arrangement and design of the hanger, it is obvious that the units, 22, of the main arch, which are adjacent the blocks, 1, may be removed and replaced 50 without disturbing the end construction.

In cases where the curtain wall is of such height and weight as to produce an excessive load on the I beam, 15, the wall may be supported by auxiliary beams im- 55 bedded therein, and this is the usual and ordinary practice followed.

For the purpose of clearly illustrating the present invention, we have shown our end construction in connection with a suspended arch of the form described and claimed in our copending application Serial No. 631,935, but no claims are made herein to the subject matter of that application.

Having thus described our invention in 60 its preferred form and embodiment, we wish

it understood that changes in the details of parts and arrangements thereof may be made without departing from the scope and spirit of the invention as defined in the appended claims. 70

What we claim is—

1. As an article of manufacture, a hanger for a furnace arch block, comprising a metal angle provided with lugs adapted to engage adjoining sides of said block, and means for pivotally engaging a supporting means. 75

2. As an article of manufacture, a hanger for a furnace arch block, comprising a metal angle adapted to receive an edge of said block therein, inwardly projecting lugs at 80 the edges of the angle adapted to engage said block in recesses provided therein, and means disposed from the vertex of said angle for pivotally engaging a supporting means. 85

3. In a furnace arch construction, the combination with a supporting beam provided with a hook receiving edge, of a metal hanger for a refractory block suspended therefrom; said hanger being provided with means for pivotally engaging said edge, and having a portion extending under and normally in contact with the bottom of said beam, whereby rotation of said hanger in one direction is prevented. 90

4. In a furnace arch construction having a main arch and a curtain wall associated therewith, a corner construction intermediate the arch and wall comprising an axially suspended block swinging freely under the expansive thrust of the main arch, and forming, independent of said main arch, a support for a portion of said curtain wall. 100

5. In a furnace arch construction, the combination with a refractory block forming an end unit for said arch, of a metal hanger adapted to be pivotally suspended from a supporting beam and provided with angular portions engaging an edge of said beam and grasping into adjoining faces of 110 said block. 105

6. In a curtain wall construction for a furnace arch, comprising a supporting means including a channel having upturned flanges; a block, forming a support for a portion of said wall, suspended from a flange of said channel by means of an angular hanger pivotally engaging a flange of said channel and extending partially around said block and the web of said channel, 120 whereby said block and hanger may swing freely away from said channel but movement in the opposite direction is prevented; and an expansion joint intermediate said block and an independently supported portion of said wall for absorbing the movement of the block. 125

7. An end wall construction for a furnace arch comprising a beam provided with an upwardly extending flange and forming 130

an independent support for the portion of said wall superimposed thereon; a course of blocks suspended below said beam by means pivotally engaging said flange and 5 having a portion disposed from said flange and retained against the bottom of said beam by the weight of said blocks, whereby said course of blocks is adapted to form a stable support for a portion of said wall 10 resting thereon.

8. In a furnace arch, a corner construction intermediate angularly disposed portions of said arch comprising a block, a hanger for said block, and a supporting 15 means for said hanger; said means including an axis for pivotally suspending said hanger to swing freely in one direction and means for preventing movement of said hanger in a counter direction.

20 9. In a furnace arch construction the combination with a main arch portion of an end block therefor and axially suspended means supporting said block and swinging freely under the expansive thrust of the 25 main arch; said means being provided with portions coacting with a supporting means for said block to limit the counter swing thereof.

10. In a furnace arch construction, the

combination with a main arch portion of an end block therefor forming a support 30 for a superimposed wall, and an axially suspended hanger for supporting said block to swing freely under the expansive thrust of the main arch; said hanger being provided with means fixedly securing it to said 35 block and means coacting with a supporting means therefor to limit the counter swing of said block and maintain said wall substantially vertical.

11. A hanger for a furnace arch block 40 comprising a body portion having angularly disposed members, lugs projecting from said members at substantially right angles to each other and adapted to grasp into adjoining angularly disposed faces of 45 a block, and means for attaching said hanger to a supporting means.

12. A hanger for a furnace arch block comprising a metal angle provided with lugs projecting inwardly from the legs of 50 said angle adapted to grasp into adjoining sides of a rectangular block, and means for attaching said hanger to a supporting means.
